UNITED STATES PATENT OFFICE.

G. TAGLIABUE, OF NEW YORK, N. Y.

IMPROVEMENT IN HYDROMETERS.

Specification forming part of Letters Patent No. 58,913, dated October 16, 1866.

To all whom it may concern:

Be it known that I, G. TAGLIABUE, of 298 Pearl street, in the city, county, and State of New York, have invented a new and Improved Hydrometer; and I do hereby declare that the following is a full, clear, and exact description thereof, which will enable others skilled in the art to make and use the same, reference being had to the accompanying drawing, forming a part of this specification.

The drawing represents a longitudinal central section of this invention.

This invention consists in a hydrometer which has a lump of metal or other suitable material secured in its main bulb, in such a manner that said lump will firmly adhere to the inner surface of the glass, and the secondary bulb used in ordinary hydrometers for the purpose of holding shot or mercury can be dispensed with. The length of the bulb is thereby materially diminished, and an additional space is obtained for the scale without increasing the aggregate length of the instrument.

A represents a hydrometer, made of glass or any other suitable material. In the bulb *a* of this hydrometer a lump, *b*, of metal or other suitable material is firmly secured, and the additional bulb or compartment, which

in ordinary hydrometers serves to confine the shot or mercury, can be dispensed with.

The lump *b* is made of metal, or an alloy of metals, which will fuse at a low temperature; and if the metal is placed in the bulb and the bulb is heated sufficiently high, said metal will melt and adhere to the glass or other material from which the hydrometer is made.

By dispensing with the additional bulb or compartment, I am enabled to increase the length of the scale without producing an increase in the aggregate length of the entire instrument.

My instruments can be packed up in a smaller compass than instruments of the ordinary construction, and a less depth of liquid is required in measuring than with an ordinary hydrometer.

What I claim as new, and desire to secure by Letters Patent, is—

A hydrometer having a lump of metal or other suitable material firmly secured to the inner surface of the bulb, substantially as and for the purpose described.

GIUSEPPE TAGLIABUE.
